UNITED STATES PATENT OFFICE.

ARTHUR L. REMINGTON, OF WORCESTER, MASSACHUSETTS, ASSIGNOR TO WARP COM-
PRESSING MACHINE COMPANY, OF WORCESTER, MASSACHUSETTS, A CORPORATION
OF MASSACHUSETTS.

THREAD-TENSIONING DEVICE.

Application filed March 11, 1926. Serial No. 93,943.

My invention relates to thread tensioning devices and has for its object to provide a device of this class which is adapted to exert a frictional force on a thread, or filament, 5 passing therethrough, so that the thread may be drawn with just enough tension to keep it taut.

My improved device is particularly characterized by the fact that it is so constructed 10 that the amount of frictional force exerted on the thread can be readily adjusted within very small limits to meet varying conditions of operation. My device is further characterized by the fact that it presents 15 smooth and unbroken surfaces to the thread, so that there is no possibility of a thread becoming accidentally entangled therein, the surfaces of the device being so formed that any tendency of the thread to disengage 20 itself from the device as it is drawn therethrough will be opposed. The above and other advantageous features of my invention will hereinafter more fully appear, reference being had to the accompanying drawings in which 25

Fig. 1 is a perspective view illustrating the use of a thread tensioning device embodying my invention.

Fig. 2 is a view in side elevation showing 30 the device of Fig. 1 on an enlarged scale.

Fig. 3 is a plan view of the device shown in Fig. 2.

Fig. 4 is a vertical sectional view along the line 4—4, Fig. 3.

Like reference characters refer to like 35 parts in the different figures.

Referring first to Fig. 1, my device is illustrated as being employed in connection with a spool or yarn package 1, from which 40 it is desired to draw the thread 2 for any suitable purpose, as for winding on a large spool or warp beam, a portion of which is indicated at 3. When the thread 2 is subjected to a draft in the direction of the 45 small arrows, it is evident that in the absence of any other force acting on the thread, it would tend to unwind loosely from the package 1, thereby creating slack which would be undesirable if the thread is to be 50 wound tightly on the beam 3.

In order to prevent slack in the thread 2

and to insure that the thread 2 will be wound on the beam with a uniform tension, my improved tensioning device, indicated generally at 4, is disposed between the spool 1 55 and the beam 3, and if desired, the thread may be passed through suitable eyes 5, 5, in passing to and from the tensioning device 4. The arrangement shown in Fig. 1 is more or less diagrammatic and is merely one illustrative embodiment of the use of my device, it being evident that my device may be employed for many other purposes in which it is desired to place a moving thread under a slight tension, as will hereinafter appear. 60

Referring now to Figs. 2, 3 and 4, my device comprises opposed cup-shaped members 6 and 7, loosely surrounding a central arbor or sleeve 8 which is preferably made of porcelain, so that it presents a smooth 70 frictionless surface where it passes through the members 6 and 7. The sleeve 8 provides a longitudinal opening through which passes a bolt 9, whereby the sleeve may be secured to a suitable supporting bar 10 by means of 75 a nut 11 coating with the bolt 9. As shown, the bar 10 provides a recess or seat 12 for receiving and positioning the end of the sleeve 8, although the seat 12 is not absolutely essential. 80

As previously stated, the members 6 and 7 loosely surround the sleeve 8 and the upper member 7 is maintained in frictional engagement with the lower member 6 by means of a number of washers 13 received on the 85 sleeve 8 within the member 7. The members 6 and 7 are so formed that they are in engagement with each other only within a narrow annular zone determined by the extent of the flat surfaces 14 and 15 provided 90 by the members 6 and 7 respectively. The lower member 6 presents a curved surface 16 surrounding the flat surface 14, while the upper member 7 provides a similar curved surface 17, from which extends upwardly 95 a frusto conical portion 18.

As clearly shown in Fig. 2, the members 6 and 7 present smooth and unbroken surfaces when assembled on the sleeve 8, and it is evident that when the thread 2 is led from the package 1 between the curved surfaces 16 and 17 of the two members, a draft 100

on the thread beyond the device will cause the thread to be held between the opposed flat surfaces 14 and 15. The thread will therefore be subjected to a frictional force as it is drawn through the device, which results in a slight tension being imparted to the thread as it leaves the device. This tension insures that a thread will be wound on the beam 3 uniformly, and it is evident that 10 when a number of devices are employed for several packages 1, the devices can be so adjusted as to insure the same tension in each thread.

The employment of a number of washers 15 13 for each device makes it possible to very closely regulate the frictional engagement of the flat surfaces 14 and 15 with the thread as it passes therebetween, thereby adapting the device to meet varying conditions of operation. It is also apparent that the 20 rounded surfaces 16 and 17 will serve to guide the thread between the opposed surfaces 14 and 15 and that there will be no tendency for the thread to disengage itself 25 from the device and become entangled. Furthermore, the conical form of both members 6 and 7 opposes any tendency for the thread to creep either up or down, and actu-

ally serves to direct the thread between the surfaces 14 and 15.

30

I claim:

In a thread tensioning device, a bolt, a porcelain sleeve surrounding said bolt, an inverted cup shaped member loosely surrounding said sleeve, said cup shaped member having its cylindrical surface and its base surface joined by a gently curving surface, a second cup shaped member with its base resting on the base of said first cup shaped member around a narrow annular zone, said second cup shaped member having an upwardly extending hollow portion of frusto-conical shape, said frusto-conical surface merging into the base of said second cup shaped member by a gently curved surface, 45 and a plurality of weights located inside said second cup shaped member around the porcelain sleeve, the whole device being readily threaded and offering a resistance to the passage of thread that is determined by 50 the number of weights in the second cup shaped member, the porcelain sleeve offering practically no resistance.

Dated this sixth day of March, 1926.

ARTHUR L. REMINGTON.
